(57) **ABSTRACT**

In an analog signal compression method with digital compression and digital expansion of linear based or sine-based linear signals, a signal coordination point is determined in a bi-adaptive scalable mV/step and a time/step structured plane. To accomplish this, the linear or sine-based input signal is digitized, the breaks of the digitized linear or sine-based signal are detected, and the time difference and the amplitude difference of two successive breaks of the linear or sine-based signal are determined. This permits time differences and amplitude differences of successive breaks to be value coded as a data word on the basis of adaptive scalable time-per-step tables and voltage-per-step tables so that the time-per-step tables and the voltage-per-step tables are selected depending on the absolute value of the determined time difference and amplitude difference, thus producing compressed data. An associated expansion method for reconstructing the original analog signal is also disclosed.

METHOD FOR COMPRESSION AND EXPANSION OF ANALOGUE SIGNALS

This application claims the priority of European Patent Application 07 010 842.8, filed Jun. 1, 2007, the entire disclosure of which is incorporated herein by reference.

BACKGROUND AND SUMMARY OF THE INVENTION

This invention relates to methods for digital compression and digital expansion of linear based or sine-based signals (e.g. audio or other signal types) by determination of a signal coordination point in a bi-adaptive scaleable mV/step and a time/step structured plane.

The general principle of digital signal data flow will be described with reference to FIG. 1. Transporting the input signal information via satellite, or storing the input signal information in memory, requires an “analogue,” or analog, signal source c1 (analog transducer signal, e.g. output of an analog strain measurement or an analog sine-based signal source (e.g. audio from a microphone output), which will be transferred at d1 to the signal coder c2 (signal digitizing, compression) and back to a signal decoder c3 (signal decompression and analogizing), and to an analog signal output c4 (e.g. fed to an amplifier and a loudspeaker—not shown).

For all applications, it is important to transfer a maximum signal quality at a minimum data rate.

An object of this invention is to create a method for compression and expansion of linear based analog signals (e.g. non-audio based signals) or sine-based analog signals (e.g. audio based signals) that provide a minimal loss of signal characteristics at a very low data rate.

This object is achieved by way of a method for digital compression and digital expansion of linear or sine-based signals by determination of a signal coordination point in a bi-adaptive scaleable mV/step and a time/step structured plane. The method includes digitizing an analog input signal, detecting breaks of the digitized input signal, and determining a time difference and an amplitude difference of two successive breaks of the input signal. The time difference and the amplitude difference of successive breaks are value coded as a data word based on adaptive scaleable time-per-step tables and voltage-per-step tables, and the time-per-step tables and the voltage-per-step tables are selected depending on an absolute value of the time difference and amplitude difference determined so as to produce compressed data. Preferred embodiments of the invention, as well as a corresponding expansion method, are also claimed.

In an input signal compression method according to the invention, the input signal is digitized via an A/D converter, the breaks (maximum values or kinks in the signal) of the digitized input signal are detected, and the time difference and the amplitude difference of two successive breaks of the input signal are determined.

The time difference and the amplitude difference of successive breaks are value coded as a data word on the basis of scaleable time-per-step tables and scaleable voltage-per-step tables, with the time-per-step tables and the voltage-per-step tables being selectable depending on the absolute break position differences in the mV/step and time/step structured planes, resulting from the determined time differences and amplitude differences of the detected input signal breaks.

Thus, by using adaptive scaleable tables, depending on the time difference and associated amplitude difference, it is possible to build a two dimensional time-per-step and voltage-per-step structured plane for every successive break posi-

tion of the input signal. Based on this procedure, the data rate of the input signal coding process can be dynamically adapted to the input signal frequency and the signal amplitude for every break-to-break distance.

As a consequence, the necessary memory for storing the compressed audio data will decrease. On the other hand, the input signal recording time at a given memory size will increase.

By way of the invention, it is possible to transfer mechanical sourced signals (linear based signals) that are particularly relevant to mechanical defect investigation of industrial machines (e.g. turbines, gears, analog sensors) as well as human vocal-based audio (sine-based signals).

These and other objects, aspects and embodiments of the present invention will be described in more detail with reference to the drawings.

BRIEF DESCRIPTION OF THE DRAWINGS

FIG. 1 is a block diagram of the general signal acquisition flow as described in the introductory part of this specification,

FIG. 2 is a functional flow diagram showing the data compression method according to the invention,

FIG. 3 is a schematic diagram regarding break detection according to the invention,

FIG. 4 is a schematic diagram regarding a combined plateau/break detection according to the invention,

FIG. 5 shows examples of a time-per-step table and a voltage-per-step table,

FIG. 6 is a schematic diagram showing digital code generation according to the invention with an analog input signal, a linear signal after break detection, and coded digital output,

FIG. 7 is a schematic diagram showing optimized digital code generation based on the coded digital output according to the invention,

FIG. 8 is a functional flow diagram showing the data expansion method according to the invention,

FIG. 9 is a schematic diagram showing reconstruction of the linear based digital signal code according to the invention,

FIG. 10 is a schematic diagram showing reconstruction of the original analog signal according to the invention with a linear based digital signal code, a linear based output signal, and a sine-based output signal, and

FIG. 11 shows analog signal sample diagrams generated by compression and expansion methods according to the invention.

DETAILED DESCRIPTION OF THE INVENTION

50 Analog Signal Coder

An analog signal coder using the compression method according to the invention converts a linear or sine-based signal from the analog input a1 (FIG. 2) to a digital data stream into the digital output a15 (FIG. 2).

55 Break Detection

The input signal b1 (FIG. 2) is processed via a A/D analog to digital converter a2 (FIG. 2) and a low pass filter a2 (FIG. 2) to reduce frequencies above the frequency spectrum that is to be processed. The output b2 (FIG. 2) of the low pass filter is sent to a break detection unit a3 (FIG. 2).

A signal break according to the invention is defined as any signal direction change. Consequently, this definition covers not only local minimums or local maxima but also any kind of breaks combined with plateaus (see several examples shown in FIG. 4). The time difference e1 (FIG. 3) between two breaks is measured and the amplitude difference e2 (FIG. 3) between the same two breaks is measured. The break detec-

tion unit a3 (FIG. 2) will detect if the input signal has a linear or sine-based structure. The linear or sine-based signal condition information ('linear-based signal mode' or 'sine-based signal mode') a4 (FIG. 2) is sent, at b4 (FIG. 2), directly to the configuration command coder a13 (FIG. 2), which will send a signal-type identification command b13 (FIG. 2) into the digital output a15 (FIG. 2), i.e. a data stream.

After verification at a4 (FIG. 2) as to whether the input signal is linear based or sine-based, the subsequent processing of the digitized input signal at b3b (FIG. 2) will be identical for both types of signal types (i.e. linear based signals or sine-based signals).

The output of the break detection process at b3b (FIG. 2) that forms the basis for the further processing is a linear segment e3 (FIG. 3), marked by two absolute defined break 15 positions.

Speech Gap Detection

Optionally, the process can enable or disable plateau coding. Hence, as a next step a5 (FIG. 2), it is checked if the signal 20 plateau detection was enabled or not.

If plateau coding is selected, it will be checked, a7 (FIG. 2), if two successive breaks f2, f3 (FIG. 4) of the linear signal b3 (FIG. 2), f1 (FIG. 4) are at the same analog amplitude level a7 (FIG. 2). If this is the case, the break-to-break time f4 (FIG. 4) will be prepared at a6 (FIG. 2) to be coded as a plateau b6 (FIG. 2).

Signal Compression/Coding

If no plateau signal applies, as at b7b (FIG. 2), or if no 25 plateau coding is selected, as at b5b (FIG. 2), then the break-to-break times e1 (FIG. 3) and the break-to-break amplitudes e2 (FIG. 3) will be measured at a8a, a8b (FIG. 2) and value coded at a9 (FIG. 2), g1 (FIG. 6), g1a (FIG. 6) on the basis of an adaptive scaleable time-per-step table (see FIG. 5) and on the basis of a adaptive scaleable voltage-per-step table (see FIG. 5 again) into one data word, determined by the signal 30 break point position in a bi-adaptive structured plane, as shown at g1a, g2a, and g3a in FIG. 6 (the data contained in the columns 'hex' and 'decimal' of FIGS. 6 and 7 show the coded data in decimal code and hex code respectively—these columns are provided for information purposes only and do not form part of the actual code). A scale change b9a (FIG. 2) of the time-per-step table or the voltage-per-step table will be done at a9 (FIG. 2) if the input signal can not be projected into the actual defined mV/step and a time/step structured plane (because of minimum or maximum value overrun).

On top of this generated data word, one control bit (for switching between command and data) g0 (FIG. 6), b9b (FIG. 2) will be inserted into the data stream. In FIG. 5, examples of a time-per-step table and a voltage-per-step table are shown. The sample time-per-step table of FIG. 5 consists of 16 steps 35 with increments of 100 μ s.

The voltage-per-step table of FIG. 5 consists of 16 steps with increments of 100 mV. Hence, by way of example, a linear segment (shown on the left hand side of FIG. 5), having a time difference of 1000 μ s=10*100 μ s and a voltage difference of 1000 mV=10*100 mV, will be coded in the format shown in FIG. 6—see the data words g1a, g2a, and g3a (FIG. 6). Each data word has a leading control bit g0 (FIG. 6) indicating that the data word is either a data word (0) or a command word (1). With the mV/step and the time/step tables shown in FIG. 5, a maximum value of 1600 mV or 1600 μ s, respectively, can be coded. For values beyond 1600 mV or 1600 μ s, or considerably smaller than 100 mV or 100 μ s, a different mV/step and a different time/step table, having other adaptive increments, will be selected. As a consequence the data rate is dynamically adapted to the frequency of the analog input signal to be coded.

Code Optimizing

The currently generated break position vector code b9b (FIG. 2) will be checked at all (FIG. 2) against the previous break position vector code a15 (FIG. 2) to identify identical 5 break position vectors (the vector code contains no absolute value information and therefore the compression can be done very simply), as is the case in the example according to FIG. 6 (three consecutive identical data words g1a, g2a, g3a). As long as identical information is detected at b11b (FIG. 2), a 'repeat last data word' command word b12 (FIG. 2), h3 (FIG. 7) will be modified or written at a12 (FIG. 2) instead of the data word itself.

FIG. 7 shows the constitution of such a 'repeat last data word' command word h3 in detail. The first part (high nibble) '1000' coded in hex-code generally indicates the type of command word (in this case a 'repeat last data word' command word). The second part (low nibble) '0010' also coded in hex code indicates a repeat factor, i.e. the number of times 20 the previous data word h2 (FIG. 7) should be repeated (in the present case, two times)

Setup Configuration

The set up and configuration after power-on and the input 25 of date, time and channel information (e.g. sensor number or dedicated analog signal input channel) into the digital output a15 (FIG. 2) is done via the command coder a13 (FIG. 2), b13 (FIG. 2) controlled by the configuration command input a10 (FIG. 2), b10 (FIG. 2).

Signal Decoder

In order to reconstruct the original analog signal from the 30 coded linear or sine-based signal, the following decoding process may be applied.

A functional flow diagram of the recorded or transmitted 35 coded digital data decoding process is shown in FIG. 8. The decoder will convert the coded data words from the digital input k1 (FIG. 8) into a linear based or sine-based output signal k16 (FIG. 8).

Decoding Setup Configuration

The input signal m1 (FIG. 8) from the digital input k1 (FIG. 40 8) is checked at k2 (FIG. 8) for configuration of power-on set up and date, time, and channel information (e.g. sensor number or dedicated signal input channel). The configuration commands will be decoded at m2b (FIG. 8) in the configuration command decoder k3 (FIG. 8) and will be directly transferred at m3 (FIG. 8) to the configuration command execution output k4 (FIG. 8).

Decoding of (Signal Specific) Commands

The data and command decoder k6 (FIG. 8) separates the 45 incoming data stream m2a (FIG. 8) into either signal data m6a or mV/step and time/step table commands m6b, m6c or other commands m6d. Controlled by the command decoder k6, the units k7, k8 and k9 control the selection of the time table (k7: time-per-step) and the value table (k8: voltage-per-step), and may control additional signal control commands 50 k9 (e.g. plateau information). The table output m7, m8, or m9 is used at k10 to reconstruct the original linear or sine-based data (e.g. audio or other signal types).

Decoding of Signals

The decoding of the digital input code is done k10 (FIG. 8) 55 by expanding the optimized code represented in FIG. 9a (i.e. containing 'repeat last data word' command words) to not optimized (expanded) linear based digital signal code n1 (FIGS. 9b and 10) consisting of break time differences and break amplitude differences. The optimized code shown in FIG. 9a corresponds to FIG. 7. By using the information of the 'repeat last data word' command word h3 (FIG. 9a), the expanded code of FIG. 9b, consisting of three identical con-

secutive data words, is generated. The expanded code shown in FIG. 9b corresponds to FIG. 6.

The linear based code (FIG. 9b) is expanded at k10 (FIG. 8) by decoding of break positions via the selected time-per-step table and voltage-per-step table used for the coding of the original analog input signal. The result of this expansion process is a linearized signal n1 (FIG. 10). If a linear output signal is required as n1 (FIG. 10) or k11 (FIG. 8), the output from the decoding of break (peak) position function m10 (FIG. 8) can be directly forwarded at m11a (FIG. 8) via the D/A converter k15 to the output k16.

For a sine-based output signal n2 (FIG. 10), the linear output code m10 (FIG. 8) from the decoding of break position k10 (FIG. 8), function will be checked for plateau data words k12 (FIG. 8). If plateaus are detected at m12b (FIG. 8), the plateau time must be recreated and filled with white noise at k13 (in order to improve the ear adaptation time) and transferred at m13 to the D/A converter k15.

Sine-based coded data m12a will be reconstructed at k14 to sine-based analog signal n2 (FIG. 10) by laying a cosine function over each linear break-to-break segment g1, g2 and g3 (FIG. 6), and n1 (FIG. 10). The analog output k16 (FIG. 8) is driven by a D/A digital to analog converter k15 (FIG. 8).

FIG. 11 shows sine-based sample diagrams generated by the compression and expansion methods according to the invention.

FIG. 11a shows an unfiltered (true) sine-based input sample as the input signal of the compression process.

FIG. 11b shows the filtered and linearized sine-based signal generated from the signal of FIG. 11a.

FIG. 11c shows the reconstructed sine-based analog signal as the output signal of the expansion process.

The foregoing disclosure has been set forth merely to illustrate the invention and is not intended to be limiting. Since modifications of the disclosed embodiments incorporating the spirit and substance of the invention may occur to persons skilled in the art, the invention should be construed to include everything within the scope of the appended claims and equivalents thereof.

The invention claimed is:

1. An audio signal compression method, comprising: digitizing an audio input signal, checking whether the audio input signal is linear-based or sine-based,

detecting all peaks of the digitized audio input signal, determining a time difference and an amplitude difference of successive peaks for all pairs of successive peaks of the digitized audio input signal,

value coding the time difference and the amplitude difference of all successive peaks as a data word based on selectable time-per-step tables and voltage-per-step tables, and selecting the time-per-step tables and the voltage-per-step tables depending on an absolute value of the time difference and amplitude difference determined so as to produce compressed data.

2. The method according to claim 1, wherein the audio input signal is checked to determine if signal levels at two successive peaks are the same, and wherein the time difference between the two successive peaks is coded as gap information when the signal levels at the two successive peaks are the same.

3. The method according to claim 2, wherein a value-coded data word is compared with a previous value-coded data word, and wherein a repeat command word, instead of a data word, indicating how many identical successive break position vectors were detected is generated when identical successive value-coded data words are detected.

4. The method according to claim 3, wherein compressed data are expanded using the selectable time-per-step tables and voltage-per-step tables.

5. The method according to claim 4, wherein the compressed data are expanded using the coded gap information.

6. The method according to claim 4, wherein the compressed data are expanded using the repeat command word.

7. The method according to claim 4, wherein a sine-based analog signal is reconstructed by fitting a cosine function to a reconstructed linear audio signal.
